UNITED STATES PATENT OFFICE.

ALBERT R. CHRISTMAN, OF PHILADELPHIA, PENNSYLVANIA, ASSIGNOR OF ONE-HALF
TO ELLIOT A. OBERRENDER, OF MELROSE PARK, PENNSYLVANIA.

BRICK-CLEANING MACHINE.

1,082,306.

Specification of Letters Patent. Patented Dec. 23, 1913.

Application filed December 27, 1912. Serial No. 738,852.

To all whom it may concern:

Be it known that I, ALBERT R. CHRISTMAN, a citizen of the United States, residing in Philadelphia, Pennsylvania, have invented 5 certain Improvements in Brick-Cleaning Machines, of which the following is a specification.

My invention consists of certain improvements in or additions to the brick cleaning 10 machine constituting the subject of my application for Letters Patent filed September 19, 1912, Serial No. 721,176, the objects of my present invention being to facilitate and perfect the operation of the machine and to 15 render such operation perfectly safe.

These objects I attain in the manner hereinafter set forth, reference being had to the accompanying drawings, in which—

Figure 1 is a plan or top view of the machine; Fig. 2 is a side elevation of the same looking in the direction of the arrow α , Fig. 1; Figs. 3 and 4 are side elevations, on a larger scale, illustrating the operation of a certain die and ram whereby the preliminary cleaning of a portion of the brick is effected; Fig. 5 is a top view of said preliminary cleaning die and ram; Fig. 6 is a perspective view of the brick after the preliminary cleaning of the same has been effected; 20 Fig. 7 is a longitudinal section of the main cleaning die illustrating also the manner of applying the partially cleaned brick thereto; Figs. 8, 9, 10 and 11 are diagrams illustrating in different relations to one another 25 a certain cam and a lever for moving one of the sides of the final cleaning die, and Fig. 12 is a perspective view on a larger scale of said lever.

In Figs. 1 and 2 of the drawings, 1 represents the main frame, 2 a sliding plunger with a projecting ram 3, 4 a crank shaft, and 5 a connecting rod whereby the reciprocation of such plunger by means of said crank shaft is effected, all of these parts being 45 common and therefore requiring no further or more detailed description.

Mounted upon the main frame, at one side of the machine, are three die plates 6, 7 and 8, the die plate 8 being vertical and 50 the die plates 6 and 7 horizontal and disposed one above another and with their inner edges adjacent to the face of the die plate 8. The acting faces of all of the plates 6, 7 and 8 are toothed, as shown in 55 Figs. 3, 4 and 5, and the upper horizontal

plate 6 and the vertical plate 8 are fixed in position but the lower horizontal plate 7 is, by preference, pivoted at one end and acted upon by a spring 9 so that it can yield downwardly when the pressure of the spring 60 is overcome, the extent of upward movement of said plate 7 being determined by the full expansion of the spring 9.

Projecting from one side of the plunger 2 through a suitable guide slot in the corresponding side of the machine frame is an arm 10 which carries a ram 11, the latter, on the back stroke of the plunger, being adapted to pass between the die plates 6 and 7 and in front of the die plate 8 at the side 70 of the machine. The die plates 6 and 7 are relatively shallow but can receive between them a few inches of one end of the brick to be cleaned, and the acting faces of said plates are tapered so as to be further separated from one another at one end than at the other, as shown in Fig. 3. An attendant grasping an uncleared brick at one end can, therefore, without any risk of injury, place its opposite end between the die plates 75 80 85 90 95 100 105 110 115 120 125 130 135 140 145 150 of a coiled spring 18, as shown in Fig. 7. The top plate 17 can, however, be raised, when desired, against the pressure of the spring 18, the means employed in the present instance for this purpose being a rod 19 pivotally connected at its lower end to the die plate 17 and likewise connected at its upper end to the forward arm of a lever 20 which is pivotally mounted upon a standard 21 projecting upwardly from the slide 13, as shown in Fig. 7.

As the slide 13 is moved back and forth, the rear arm of the lever 20 is acted upon by a cam bar 22, fixedly mounted upon the top 15 of the cross frame 14. The rear arm of the lever 20 has a hinged section 23 (Fig. 12) normally kept in line with the rest of the arm by a spring 24 but capable of yielding upwardly when subjected to pressure from 20 below.

The action of the cam bar upon the lever 20 is as follows, reference being had to Figs. 8, 9, 10 and 11: When the slide 13 is at that 25 limit of its movement where the die 12 is in line with the ram 3 the lever 20 occupies the relation to the cam bar 22 shown in Fig. 8, that is to say, it is beyond the end of the cam bar and its rear arm is below the under surface of the elevated end of said cam bar. 30 As the die carrying slide 13 moves to the left, the lever 20 is carried beneath the cam bar 22, as shown in Fig. 9, and is acted upon thereby so as to depress the rear arm of the lever and raise the forward arm of the same, 35 thereby lifting the upper die plate 17. Said upper die plate is retained in the elevated position until the slide 13 has almost reached the limit of its movement to the left, whereupon the rear arm of the lever 20 passes 40 from under the cam bar 22, as shown in Fig. 10, and, being free to rise, permits the upper die plate 17 to be depressed by the spring 18. On the movement of the slide 13 to the 45 right the rear arm of the lever 20 passes over the top of the cam bar 22 and its pivoted member 23 is raised by contact with the elevated end of said cam bar, as shown in Fig. 11, but when the lever passes beyond the cam bar, said pivoted member snaps 50 back to its normal position so as to pass beneath the cam bar on the next movement of the slide 13 to the left.

Immediately in front of the die 12, when the latter is in the position shown in Fig. 55 1, is a rail or bar 26 which is flush with or slightly above the bottom plate 16 of the die. An attendant holding a partially cleaned brick, such as shown in Fig. 6, may, therefore, rest the cleaned end of said brick 60 on said bar so that said cleaned end will project beyond the bar and toward the die 12, this cleaned projecting portion of the brick, when the die 12 reaches the position shown in Fig. 1, being between the forward ends

of the lower and upper plates 16 and 17 of 65 the die, as shown in Fig. 7.

As the die on its movement to the left approaches the brick the upper die plate 17 is raised so as to be free from contact with the upper face of the brick, but, just as the die 70 reaches the limit of its movement, the lever 20 passes from under the influence of the cam bar 22 and the upper die plate 17 snaps down upon the top of the brick and securely confines said brick between the upper and lower 75 plates of the die, whereby, as the die moves from the side of the machine toward the center of the same, it will carry the partially cleaned brick with it, and will stop with the brick in line with the ram 3. When the ram 80 advances, therefore, it will strike the rear end of the brick and will force the same through the die so as to remove the mortar from the right and left hand sides of the brick and complete the removal of the mortar from the 85 top and bottom sides of the same.

It will be noted on reference to Fig. 7 that the top and bottom plates of the die 12 project beyond the side plates 15, consequently the presence of mortar up to the end 90 of the brick on those sides which correspond with the side plates 15 of the die will not interfere with the proper placing of the partially cleaned end of the brick between the upper and lower plates of the die. 95

If desired, a bar or rail 27 may be disposed above the rail 26 for contact with the cleaned top face of the brick when the cleaned lower face of the same rests on said rail 26, thus serving to support the partially 100 cleaned brick in position to be engaged by the top and bottom plates of the die 12; even should the attendant let go of the brick before the die reaches the proper position to engage the same. The rails 26 and 27 may 105 be mounted upon the main frame 1 of the machine in any manner which will permit the lateral movement of the brick from between the same.

The machine is intended to be operated by 110 two attendants one of whom, located at one side of the machine, presents the bricks to the preliminary cleaning die and, after the partial cleaning of the brick, places it in position to be handled by the other attendant, located at the opposite side of the machine, the latter attendant presenting the partially cleaned brick in position to be clamped between the plates 16 and 17 of the finishing die 12. In neither case, however, 115 are the hands of the attendants brought into position to be struck by a moving part of the machine, or caught between a fixed and a moving part of the same, and all risk of 120 injury to either attendant is therefore overcome. 125

I claim:

1. The combination, in apparatus for

cleaning bricks, of means for cleaning the mortar from opposite sides of the brick at and near one end of the same, a die adapted to engage said cleaned surfaces of the 5 brick, and means for forcing the brick through said die so as to complete the cleaning of the mortar from said partially cleaned sides thereof.

2. The combination, in apparatus for 10 cleaning bricks, of means for cleaning the mortar from opposite sides of the brick at and near one end of the same, a die adapted to engage said cleaned surfaces of the brick, and means for forcing the brick 15 through said die so as to complete the cleaning of the mortar from said partially cleaned sides thereof, said die also having means for cleaning the mortar from the other two sides of the brick simultaneously with the completion of the cleaning of the 20 mortar from those sides of the brick which were first partially cleaned.

3. The combination, in apparatus for 25 cleaning bricks, of means for cleaning the mortar from the top and bottom sides of a brick at and near one end of the same and for simultaneously cleaning the mortar from the adjacent end of the brick, a die having 30 means for engaging said partially cleaned sides of the brick, and means for forcing the brick through said die so as to complete the cleaning of said partially cleaned sides thereof.

4. The combination, in apparatus for 35 cleaning bricks, of means for cleaning the mortar from the top and bottom sides of a brick at and near one end of the same and for simultaneously cleaning the mortar from the adjacent end of the brick, a die having 40 means for engaging said partially cleaned sides of the brick, and means for forcing the brick through said die so as to complete the cleaning of said partially cleaned sides thereof, said die also having means for 45 cleaning the mortar from the other two sides of the brick simultaneously with the completion of the cleaning of those sides which were first partially cleaned.

5. The combination, in apparatus for 50 cleaning bricks, of a preliminary die having plates projecting over the top and bottom of the brick at and near one end of the same, means for forcing the brick laterally through said die, thereby cleaning said sides at and 55 near said end, a second die adapted to engage said cleaned portions of the sides of the brick, and means for forcing the brick longitudinally through said die so as to complete the cleaning of the partially cleaned 60 sides thereof.

6. The combination, in apparatus for 65 cleaning bricks, of a preliminary die having plates projecting over the top and bottom of the brick at and near one end of the same,

means for forcing the brick laterally 65 through said die, thereby cleaning said sides at and near said end, a second die adapted to engage said cleaned portions of the sides of the brick, and means for forcing the brick longitudinally through said die so as to complete the cleaning of the partially cleaned sides thereof, said second die also having means for cleaning the mortar from the other two sides of the brick simultaneously with the completion of the cleaning of the 70 mortar from those sides of the brick which were first partially cleaned.

7. The combination, in apparatus for 75 cleaning bricks, of a preliminary die having a side plate for acting on one end of a brick 80 and top and bottom plates projecting over the brick at and near said end, means for forcing the brick laterally through said die, thereby cleaning the end of the brick and the top and bottom sides at and near said end, a second die adapted to engage the cleaned 85 portions of the sides of the brick, and means for forcing the brick longitudinally through said second die so as to complete the cleaning of the mortar from said partially cleaned sides.

8. The combination, in apparatus for 90 cleaning bricks, of a preliminary die having a side plate for acting on one end of a brick and top and bottom plates projecting over 95 the brick at and near said end, means for forcing the brick laterally through said die, thereby cleaning the end of the brick and the top and bottom sides at and near said end, a second die adapted to engage the cleaned 100 portions of the sides of the brick, and means for forcing the brick longitudinally through said second die so as to complete the cleaning of the mortar from the partially cleaned sides, said second die also having means for 105 cleaning the mortar from the other two sides of the brick simultaneously with the completion of the cleaning of the mortar from those sides which were first partially cleaned.

9. In a brick cleaning machine, the combination of a die movable to different positions and having a movable plate, a plate opposed thereto, means for yieldingly moving said movable plate of the die toward the 110 opposed plate, devices connected to the movable plate of the die, and means whereby, as the die is moved, said devices are acted upon so as to draw the movable plate of the die 115 away from the opposed plate.

10. In a brick cleaning machine, the combination of a die movable to different positions and having a movable plate, a plate opposed thereto, means for yieldingly moving said movable plate of the die toward 120 the opposed plate, devices connected to the movable plate of the die, and means whereby, as the die is moved, said devices are 125

acted upon so as to draw the movable plate of the die away from the opposed plate and are then released so as to permit the movable plate to approach the opposed plate.

5 11. The combination, in a brick cleaning machine, of a support for the brick, a die movable from and toward said support and having a movable plate, a plate opposed thereto, means for moving the movable plate 10 of the die away from the other plate as the die approaches the brick, and means for permitting said movable plate to approach the opposed plate when the die is in registry with the brick.

15 12. The combination, in apparatus for cleaning bricks, of means for cleaning opposite sides of the brick at and near one end of the same, a die adapted to engage said partially cleaned sides of the brick, means for 20 engaging and holding the partially cleaned brick when it is presented in position for said die to engage the partially cleaned sides of the same, means for thus causing the die to engage said partially cleaned sides and 25 means for forcing the brick through said die.

13. In a brick cleaning machine, a four-sided die having two of its opposed sides

projecting longitudinally beyond the other two opposed sides, whereby a brick having opposite sides cleaned at and near one end 30 may have said cleaned sides applied to and clamped between the projecting sides of the die without interference by contact of the other opposed sides of the die with mortar on the uncleared sides of the brick. 35

14. In a brick cleaning machine a four-sided die having two of its opposed sides projecting longitudinally beyond the other two opposed sides and provided with means for moving one of said projecting sides from and toward the other, whereby a brick having the opposite sides cleaned at and near one end may have said cleaned sides applied to and clamped between the projecting sides of the die without interference by contact 40 of the other opposed sides of the die with mortar on the uncleared sides of the brick. 45

In testimony whereof, I have signed my name to this specification, in the presence of two subscribing witnesses.

ALBERT R. CHRISTMAN.
